UNITED STATES PATENT OFFICE.

GEORGE MESSINGER, OF PROVIDENCE, RHODE ISLAND.

POWDER-BOX COVER.

938,161.

Specification of Letters Patent. Patented Oct. 26, 1909.

Application filed October 9, 1908. Serial No. 456,917.

To all whom it may concern:

Be it known that I, GEORGE MESSINGER, of Providence, in the county of Providence and State of Rhode Island, have invented 5 certain new and useful Improvements in Powder-Box Covers, of which the following is a specification.

This invention relates to boxes for sprinkling pulverized material, and has especial 10 reference to the use of toilet powder, in which the upper end of the box is provided with a closure consisting of a fixed member having discharge perforations or openings, and a member having discharge perforations 15 or openings movable over said fixed member to cause the perforations of said members to register with each other, or to close them.

The invention has for its object to provide 20 a box of this character by means of which powder may not only be discharged in streams therefrom when it is desired to use it for sprinkling, but also may be used to pour out the powder in a single stream instead of in several streams.

25 The invention consists in an improved box for discharging pulverized material, so constructed and arranged that it may be used either to sprinkle the powder, or to pour it out in a single mass, as hereinafter 30 set forth and claimed.

In carrying out the invention, a box or receptacle of suitable size and shape is provided having its upper end provided with a closure consisting of two members, one of 35 which is stationary, and the other movable over the fixed member, each member having a number of small openings or holes in alinement with each other to permit of the discharge of the material in the box, when 40 tilted, in streams, and each member having an enlarged opening in alinement with each other to permit of the discharge of a mass of the material in a single stream when the box is tilted, while the small openings are closed. 45 The movable member may be so operated as to open the small openings and close the large opening, or close the small openings, and open the large opening, as it is desired to use the box to sprinkle the material, or 50 pour it out in mass in a single stream.

Referring to the accompanying drawings, which illustrate the manner of carrying out the invention,—Figure 1 is a plan view of the upper end of a box constructed in accordance with this invention, showing the 55 openings in position for discharging the

contents thereof in a number of streams and sprinkling the same. Fig. 2 is a view of the box in elevation with its upper end portion in vertical section on the line $x-x$ of Fig. 1. 60 Fig. 3 is a plan view of the upper end of the box showing the parts in position for discharging the material in a single stream only. Fig. 4 is a view in vertical section of the upper portion of the box on the line $y-y$ of Fig. 3. Fig. 5 is a plan view of the top of the box showing all the openings closed. Fig. 6 is a vertical section of the upper portion of the box on the line $z-z$ of Fig. 5. Fig. 7 is a detail view in perspective 70 of the movable member detached.

1 indicates a receptacle of suitable shape, size and material, and provided with a closure at its top, preferably consisting of a flanged cover 2 fitting over the upper open 75 end of the box, and a thin plate 3 in the form of a disk pivotally secured to rotate on the under side of the cover 2 by means of the central pivot pin 4. The cover 2 is provided with a number of small holes 5, and 80 the plate 3 with a number of correspondingly shaped small holes 6 arranged to be moved into alinement with the holes 5. The cover 2 is also provided with an enlarged opening or hole 7 of any size or shape desired, and the plate 3 is provided with a corresponding opening 8, which is adapted to register with the opening 7 when the holes 5 are closed by the plate 3, and which is closed by the cover 2, when the holes 5 are in alinement with the holes 6. 90

Any suitable means may be employed for operating the plate 3, and as here shown, a button 9 is provided, mounted on the upper end of a pin 10, projecting through a curved 95 slot 11, and secured to the plate 3. In Fig. 1 the holes 5 and 6 in the cover 2 and plate 3 are shown in alinement, and the opening 7 in cover 2 closed. With this arrangement of the openings, the box may be used to discharge the powder therein in a number of streams, for sprinkling purposes. In Fig. 3 the holes 5 are shown as closed by the plate 3, and the holes 7 and 8 in alinement, whereby the powder may be poured out in a 100 single stream when that is preferable to sprinkling. It will thus be seen that by actuating the plate 3 by means of the button 9, the plate 3 may be pushed to the position shown in Fig. 1, to open the holes 5, and 110 close the hole 7 to adapt the box to be used to sprinkle powder, and be pushed to the

position shown in Fig. 3 to close the holes 5 and open the hole 7 to permit the powder to be poured out in a single stream only; and to be pushed to the position shown in Fig. 5 to close all of the openings.

While the construction of the closure, as set forth, is preferable since the cover 2 with the movable member attached thereto can be readily removed to fill the box with powder, 10 yet the relative construction and arrangement of the fixed and movable members of the closure may be varied without departing from the essential feature of the invention. It is obvious also that the size and relative 15 arrangement of the openings 5 and 6, and 7 and 8 may be changed to adapt the box to be used with granulated or other divided substances besides powder.

The pin 10 and slot 11 constitute stop 20 members which permit a limited rotative adjustment of the plate 3, the arrangement being such that when the plate is at one extreme of its rotative adjustment, all the smaller openings are open, so that they are 25 adapted to discharge powder simultaneously, the larger openings being closed, as indicated in Fig. 1; and when the plate is at the opposite extreme of its rotative adjustment, all the openings are closed, as indicated in 30 Fig. 5; and when the plate is at an intermediate position, the smaller openings are all closed and the larger openings are open, as shown in Fig. 3, so that the box is adapted to discharge a single large stream of powder. 35 It follows, therefore, that a relatively slight rotative adjustment of the plate is sufficient to permit either the discharge of a number of small streams of powder, or the discharge of a single large stream. It will be observed 40 that the smaller openings are arranged in a group which is distributed uniformly around the center of the cover and plate, so that when said openings are unobstructed, they are adapted to simultaneously discharge a 45 number of fine streams distributed over a

considerable area. It will also be observed that the larger openings in the cover and plate are located outside the groups of smaller openings and in close proximity to the margin of the cover, so that when the 50 larger openings are unobstructed, they permit the discharge of a single large stream of powder close to the margin of the cover, so that the stream may be conveniently deposited.

Having described the invention, I claim:

A receptacle of the character stated, having a cover and a plate bearing on the cover and rotatively connected therewith, the cover and plate being each provided with a 60 group of smaller openings uniformly distributed around the center of the cover, and with a single larger opening located outside the said group and in close proximity to the margin of the cover, stop members being 65 provided which permit a limited rotative adjustment of the plate, the arrangement of the openings and stop members being such that when the plate is at one extreme of its rotative adjustment, the smaller openings of the cover and plate are open, and the 70 larger openings closed; and when the plate is at the other extreme of its rotative adjustment, all the openings are closed; and when the plate is at an intermediate adjustment, 75 the larger openings are open and the smaller openings are closed, so that a relatively slight adjustment of the plate is sufficient to permit either the discharge of a number of small streams of powder, distributed 80 around the center of the cover, or the discharge of a single large stream near the margin of the cover, or the closing of the cover to prevent any discharge.

In testimony whereof I have affixed my 85 signature, in presence of two witnesses.

GEORGE MESSINGER.
